ATTORNEY

UNITED STATES PATENT OFFICE

KRIST KNUDSEN, OF SEATTLE, WASHINGTON

SWIMMING APPLIANCE

Application filed October 10, 1927. Serial No. 225,355.

My invention relates to improvements in swinging appliances and the object of my invention is to provide swimming appliances that may be worn on the feet, and that will 5 greatly facilitate the progress of a swimmer in the water.

Another object is to provide swimming appliances which are constructed of buoyant material thereby making it easier for a swimmer 10 wearing the same to keep his head above water.

Another object is to provide swimming appliances of this nature which do not hamper the free and easy movement of the 15 feet, which are easily dragged forward through the water with slight resistance and which offer a maximum resistance to the water on the backward or propelling stroke of the leg.

20 The bare feet afford a relatively small area that may be forced against the water to propel the body forward in the water and it is the object of my invention to provide appliances which may be worn on the feet to afford a greater area for pressure against the 25 water thereby enabling the swimmer to develop a greater efficiency in proportion to the power expended.

Other and more specific objects will be apparent from the following description taken 30 in connection with the accompanying drawings:

Figure 1 is a view in side elevation of a foot swimming appliance embodying my invention; 35

Fig. 2 is a sectional view substantially on dotted line 2—2 of Fig. 1.

Like reference numerals designate like parts throughout the several views.

40 The foot appliance embodying my invention is in the nature of a foot block 3 having a heel receptacle 4 and straps 5 for securing it to the foot. The walls of this foot block 3 are inclined or flared outwardly and said foot block is hollowed on its bottom side affording an expanding cup 6 that offers great resistance to the water on the rearward stroke of the foot and small resistance to the water on the forward stroke of the foot. The 45 bottom of said walls terminate in a plane sub-

stantially parallel to the plane of the top of the foot piece.

The construction is such as to permit the wearer to readily walk with the swimming appliance in applied position on the foot. 55 This makes it possible for the wearer to walk over that portion of the beach where there may be barnacled rocks or soft mud, while on his way to deep water.

The device serves to greatly increase the 60 efficiency of the leg stroke and since the device is preferably made of light strong wood or other suitable material which is substantially impervious to water and will be sufficiently buoyant, it especially helps the 65 swimmer at the surface of the water. Thus the device enables the ordinary swimmer to cover much greater distances and obtain much greater speed with less effort than would be possible without the appliance.

Obviously, changes may be made in the 70 form, dimensions, and arrangement of the parts of my invention without departing from the principle thereof, the above setting forth only a preferred form of embodiment.

I claim:

75 A swimming appliance embodying a foot piece whereon the foot may rest, said foot piece being of substantially the same size as the foot, means for securing said foot piece to the foot and integral flaring walls extending downwardly and outwardly from the marginal portions of said foot piece to form a dish like cavity, the bottoms of said walls terminating in a plane parallel to the plane 80 of the top of the foot piece.

85 In witness whereof I hereunto subscribe my name this 3rd day of October, A. D. 1927.

KRIST KNUDSEN.
